THE COLUMBIA PLANOGRAPH CO., WASHINGTON, D. C.

UNITED STATES PATENT OFFICE.

LEWIS H. LANIER, OF NEWPORT, KENTUCKY, ASSIGNOR OF ONE-THIRD TO THOMAS J. LEEN AND ONE-THIRD TO CHARLES KOESTER, BOTH OF CINCINNATI, OHIO.

BASE-BALL-THROWING MACHINE.

1,187,434.

Specification of Letters Patent. Patented June 13, 1916.

Application filed August 28, 1915. Serial No. 47,761.

To all whom it may concern:

Be it known that I, LEWIS H. LANIER, a citizen of the United States, and a resident of the city of Newport, in the county of Campbell and State of Kentucky have invented certain new and useful Improvements in Base-Ball-Throwing Machines, of which the following is a full, clear, and exact description, reference being had to the accompanying drawings, forming part of this specification.

My invention relates to baseball throwing machines. In machines of this character, the desired object is to throw a ball at a desired speed, and with as much accuracy as if it were pitched by hand.

In an application for patent formerly filed by me on March 24, 1915, Serial No. 16,797, I described a mechanism for throwing a ball comprising a resilient arm, spring-actuated against a curved abutment. The arm and abutment were alike pivoted on a post so as to be swung at the desired angle for delivering the ball to a given point, and the said parts were also pivoted so as to swing upwardly or downwardly so as to throw the ball at the given elevation.

It is the object of this invention to provide modifications of said former device, whereby more security against breakage of parts is gained, whereby provision is made against irregularities of the ball cover resulting in undue curving of the ball in its flight, and whereby means will be had so that a batter may tell that the ball is being thrown, said means comprising preferably a manikin, actuated by the throwing arm.

It is also the object to provide mechanism for pulling back the arm for each throw.

These objects and other advantages in construction and the like are accomplished by that certain construction and arrangement of parts to be hereinafter more specifically pointed out and claimed.

In the drawings, Figure 1 is a top plan view of the machine. Fig. 2 is a side elevation of said machine. Fig. 3 is a front elevation of said machine. Fig. 4 is an end elevation thereof. Fig. 5 is a longitudinal section of the throwing arm as improved by me. Fig. 6 is a vertical section of the ball holding cup taken on the lines 6, 6, of Fig. 3. Fig. 7 is a side elevation of the manikin.

As in my former invention, the whole device is mounted on a post 1, securely

mounted on a suitable foundation. On this post, as formerly, is journaled at 2 a large horizontal shaft 3 which carries the parts for the throwing device. A hand wheel 4 on a bracket 5 on the post operates a worm that meshes with a gear 6 on the shaft journal, whereby the shaft may be adjusted to the desired angle with regard to the objective of throw.

A bracket 7 on the journal 2 supports a hand wheel 8 having a worm that meshes with a gear 9 mounted on the shaft, and by means of this mechanism the shaft may be rocked to adjust the machine for height of throw, all as in my former machine, except that in this instance the hand wheel is above instead of below the worm with which it is connected.

As in my former machine, the curved abutment 10 is fixedly mounted on the shaft 3 so that it is adjustable with the movement of the shaft. The means for operating the arm is also the same, comprising a segment gear 11, pivoted at 12 to a base 13 mounted on the horizontal shaft, said segment gear having an extended portion 14 against which the end 15 of the arm is mounted. This gear meshes as in my former case with another like gear 16, likewise pivoted to the base 13, at 17, said gear having an extending portion 18 that is pivotally connected to a double spring actuator 19. The spring actuator is mounted at its other end to arm 20 on the horizontal shaft, and the point of connection of the actuator and the portion 18 of the gear is adjustable in a series of apertures 21, all as in my former application. The arm releasing mechanism is also the same, comprising the spring plunger 22, controlled by the handle 23, said plunger arranged to rise into the first exposed tooth in the gear 11 as this gear is retracted in bringing back the arm for a throw. The teeth of this gear are covered at the bottom against access of this plunger by a plate 24 which is adjustable so as to regulate tension of the spring actuator, by regulating the distance which the arm can be brought back.

One of the new improvements in this invention comprises the means for drawing back the arm, said means likewise to be mounted on the horizontal shaft so that it can be operated at any position of the shaft.

Mounted in a housing 25 on an arm 26 mounted on the horizontal shaft by the

collar 27, is a sliding bar 28. This bar has rack teeth on its under side and at the operating side of the machine is arranged to pass under a guide arm 29 which is mounted on the shaft by a collar 30. A hanger 31 is mounted together with the base 13 on the shaft 3 and on this is rotatably mounted a gear 32 that lies under and in mesh with the rack bar. The pivot pin 33 which connects the spring actuator to the arm or extension 18 of the segment gear 16, is extended downwardly at 34. An arm 35, pivoted to the end of the rack bar, has a hook 36 which is adapted to engage over this pin at 34. The gear 32, in mesh with the bar, has an operating handle 37, and by hooking the arm 35 over the pin and revolving the gear 32, the rack bar will be retracted and will swing the gear 16 on its pivot at 17, thereby drawing back the arm until the plunger engages the gear 11 as stated. When this has taken place, a slight movement of the handle will suffice to disengage the hook from the pin and the arm will be ready to be released for a throw, by lowering the plunger by means of the handle 23. It is obvious that this mechanism will draw back the arm in position for use, no matter what the position of the horizontal shaft 30 may be, as it is mounted on the shaft in fixed relation to the other throwing parts and to the shaft, and when the shaft is moved all the parts will be moved simultaneously and to the same degree.

35 It has been found that the throwing arm, throughout the portion thereof which is bent over the curved abutment at the end of the throwing movement, after some time is liable to be injured and finally to break. 40 This is due to the constant jar at the moment of snapping the ball away, and the breakage comes along the body of the arm and also at the point where the ball holding means are secured to the arm, the securing 45 bolts therefor being liable to pull out and split up the end of the arm. Accordingly the new arm is formed as follows: The end portion 15 of the arm is narrowed at 37^a and extended at 38 to form the flexible portion 50 of the arm. This portion has laid along it and suitably riveted (not shown) on both sides the metal strips 39, 39. These strips have laid on top of them and bound down by wrapping with adhesive tape 40, the 55 outer pieces of hickory wood 41, 41. The cup 42 is provided with holes in its base 43 for securing bolts 44. It is to be mounted on the end of the arm, and as stated, if the bolts had to pass through wood alone, they 60 would gradually pull out by splitting up the end of the arm. The metal pieces, as well as giving greater tensile strength to the arm, prevent this splitting also. For this purpose, the two strips are bent out 65 over the ends of the outer layers of hickory

and back so as to reinforce them on the outside. Holes are pierced in the metal and in the wood for the securing bolts of the cup, and the bolts are passed through the reinforced end of the arm, thereby firmly and 70 permanently holding the cup in place, against the severe strain to which it is subjected. The outer pieces of hickory are thin, and it is desired to have them slide on the inner portions of the arm. The adhesive tape so holds the outer strips that they may do this, and the inner strip will slide one way and the outer strip the other each time the throwing arm is brought up against the curved abutment. The arm has 80 sufficient spring in it to snap the ball out of the cup at the end of the throw, and it is fully protected against breaking by the superimposed strips of hickory and metal.

The cup is partly the same and partly 85 improved over the cup in my former application. The idea of the former cup was to provide curved members to contact with the ball and a spring member to hold it loosely therein until the snap at the end of 90 the throw. In the present cup, the base is hollowed out so as to present a concave curvature at 45. The ball 46 when in the cup rests in this curvature, which is just the size of the standard regulation ball. The cup 95 has its outer end sloped away from the vertical at 47, so that the ball may rest against said curvature at the three sides thereof, and the fourth side is engaged by a spring 100 retaining device. This device comprises a 105 piece of bent spring metal 48 in the shape of a numeral 2, in the upper member of which is slidably mounted a spring finger 49. This finger has a smooth rounded end which contacts with the ball, and the spring 110 50 thereof is not to be very strong, as it should not hold a ball that is slightly out of shape or having roughened seams any more firmly than a new ball. Any extra pull on the ball, as it is released, will result in a 115 curving of the ball in its flight, which will result in an inaccurate pitch of the ball.

It is desired in addition to have means for indicating to a batter practising with this ball thrower when the ball is being 115 thrown. If the batter cannot see the throwing member, he is not able to tell just when the ball is coming and the machine would not be of sufficient value as a practising machine for batters. In view of the fact that the throwing arm has a rapid movement mainly concealed from the batter, it is designed to warn the batter by providing a manikin which will move contemporaneously with the throwing arm, raising its 120 arm and swinging it as if to throw a ball. A manikin, having a body 50, pivoted on a post 51, is erected in front of the machine, with one leg 52 secured along the post. A spring 53, connected to the body and to the 125

ground, serves to hold the body in a position normally facing the batter. The right arm 54 of the body is fixed and the body is connected by a rod 55 with the throwing arm 5 at 56. The left arm 57 and the left leg 58 are connected by cords 59 and 60 with the ground so that as the manikin swings away from the front, the left arm will be raised up and the left leg pulled up at the knee, 10 so as to swing forwardly (dotted lines, Fig. 7). When the arm is pulled back, the manikin will draw back his right arm and double up as a pitcher of a ball would do. As the arm is released, the rod and spring on the 15 manikin will draw it forward together with the throwing arm, and when the ball is released from the arm, and the manikin will have completed the movements of his mock throw of the ball. This will duplicate exactly 20 the movements of a pitcher and will make the machine valuable as a practice machine as well as make it valuable as a side show device, where the public may bat at balls in a fair booth and the like. The 25 rod 55 forms an accurate stop for the manikin.

It is believed that the operation and object of the various new devices of this mechanism are now apparent and that the mention 30 of equivalent structures which will not depart from the spirit of the invention is unnecessary. It is not desired that the claims be construed to mean specific structure, where such is not plainly called for 35 therein.

Having thus described my invention, what I claim as new and desire to secure by Letters Patent, is:—

1. In a baseball throwing device, a standard, a horizontal member pivotally mounted 40 on the standard, a throwing arm on the horizontal member, an abutment for the arm on said member extending parallel to said member, and means for drawing back the arm for throwing, said means also mounted on the horizontal member.

2. In a baseball throwing device, a standard, a horizontal member pivotally mounted 50 on the standard, a throwing arm on the horizontal member, an abutment for the arm on said member extending parallel to said member, means for drawing back the arm for throwing, said means also mounted on the horizontal member, means for rocking 55 said member, and means for adjusting the position of said member around the standard, for the purpose described.

3. In a baseball throwing machine, in combination with a throwing arm, a cup on said 60 arm for the ball, curved contact members in the cup for the ball, and a spring finger located below the outer edge of the cup for loosely holding the ball in the cup.

4. In a baseball throwing machine, in combination with a throwing arm, a cup on said

arm for the ball, curved contact members in the cup for the ball, and a spring finger arranged to contact with the side of the ball slightly above its median line when located in the cup, for loosely holding the ball in 70 the cup.

5. In a baseball throwing machine, a throwing arm, toothed segments connected to said arm, a spring actuator connected to the segments, and a rack connected to one 75 of the segments for actuating it to draw back the arm and means for disengaging the connection between the rack and the segments when the ball is to be thrown.

6. In a baseball throwing machine, a 80 throwing arm, toothed segments connected to said arm for operating the same, a spring actuator connected to one of the segments, and a reciprocating member, having means to engage said one segment to move it 85 against the spring tension and to draw back the arm and means for disconnecting said engaging means when the ball is to be thrown.

7. In a baseball throwing machine, a 90 throwing arm, toothed segments connected to the arm for operating the same, a spring actuator, a pivot bolt for connecting it to one of the segments, a reciprocating member, and means on the reciprocating member 95 to detachably engage the pivot bolt, as and for the purpose described.

8. In a device of the character described, a throwing arm, means on the end of the arm for holding a ball, said arm comprising 100 a plurality of strips of tough and resilient wood, and strips of metal interposed between the wood, said metal strips bent back over the end of the wooden portion to form a mounting for the ball holding means. 105

9. In a device of the character described, a throwing arm, means on the end of the arm for holding a ball, said arm comprising 110 a plurality of strips of tough and resilient wood, and strips of metal interposed between the wood, and means for loosely binding the outer wooden strips to the arm so that they have play to slide on the metal strips.

10. In a device of the character described, a throwing arm, means on the end of the arm for holding a ball, said arm comprising 115 a plurality of strips of tough and resilient wood, and strips of metal interposed between the wood, and means for loosely binding the outer wooden strips to the arm so that they have play to slide on the metal strips, comprising binding tape wound around the outside of the arm. 120

11. In a device of the character described, a throwing arm, means on the end of the arm for holding a ball, said arm comprising 125 a plurality of strips of tough and resilient wood, and strips of metal interposed between the wood, and means for loosely bind- 130

ing the outer wooden strips to the arm so that they have play to slide on the metal strips, comprising binding tape wound around the outside of the arm, said metal strips bent over the end of the wooden portions to form a mounting for the ball holding means.

12. In a baseball throwing machine, mechanism for throwing a ball, and a manikin connected to the throwing mechanism

and arranged to make the movement of throwing the ball synchronously with the throwing mechanism, said manikin having an arm arranged to swing through the air and to stop at the instant that the ball is 15 thrown, and said manikin also having a leg and an arm adapted to raise and fall together with the movement of the other arm of said manikin.

LEWIS H. LANIER.
